(57) **CLAIM**

The ornamental design for a front bumper for a motor vehicle, as shown and described.

DESCRIPTION

FIG. 1 is a front perspective view of a first embodiment of a front bumper for a motor vehicle showing our new design; FIG. 2 is a front view thereof; FIG. 3 is a rear view thereof; FIG. 4 is a right side view thereof; FIG. 5 is a left side view thereof; FIG. 6 is a top plan view thereof; and FIG. 7 is a bottom plan view thereof.

FIG. 8 is a front perspective view of a second embodiment of a front bumper for a motor vehicle showing our new design;

FIG. 9 is a front view thereof; FIG. 10 is a rear view thereof; FIG. 11 is a right side view thereof; FIG. 12 is a left side view thereof; FIG. 13 is a top plan view thereof; and, FIG. 14 is a bottom plan view thereof.

The de-emphasized and half-tone portions shown in the photographs illustrate environmental structure for the rear portion of the front bumper for a motor vehicle that forms no part of the claimed design.

1 Claim, 14 Drawing Sheets
